CLAIM

I claim the ornamental design for a vehicle wheel, as shown and described.

DESCRIPTION

FIG. 1 is a perspective view of the vehicle wheel showing my new design;

FIG. 2 is a front view of the vehicle wheel; and,
 FIG. 3 is a cross-sectional view taken along the line 3-3 of FIG. 2.

The broken lines showing the rear portion of the vehicle wheel are included for the purpose of illustrating environment and forms no part of the claimed design.
